UNITED STATES PATENT OFFICE.

GEORGE F. FOLSOM, OF BOSTON, MASSACHUSETTS.

DESIGN FOR A SNOW-GUARD.

SPECIFICATION forming part of Design No. 28,655, dated May 17, 1898.

Application filed March 17, 1898. Serial No. 674,263. Term of patent 14 years.

To all whom it may concern:

Be it known that I, GEORGE F. FOLSOM, a citizen of the United States, and a resident of Boston, county of Suffolk, and Commonwealth of Massachusetts, have invented and produced a new and original Design for a Snow-Guard, of which the following is a specification.

The drawing shows in perspective a snow-guard, illustrating my design.

The leading feature of my design for a snow-guard consists in a straight shank bent upon itself to form an inverted **U** and then oppositely bowed to present two loops laterally extended from the shank, the connection between the loops passing through the **U**.

In the drawing the straight shank *a* is bent upon itself at one end in **U** form at *a'* and

then oppositely bowed to present two loops *a²* *a³*, extended laterally from the shank, the ²⁰ bowed portion being substantially like the numéral **8** upon its side, with the connection between the loops passing through the **U**.

Having fully described my invention, what I claim, and desire to secure by Letters Patent, is—

The design for a snow-guard, substantially as herein shown and described.

In testimony whereof I have signed my name to this specification in the presence of ³⁰ two subscribing witnesses.

GEO. F. FOLSOM.
